(57) **CLAIM**

The ornamental design for camouflage tree bark relief hunting clothing, as shown and described.

DESCRIPTION

FIG. 1 is a front elevational view of tree bark relief hunting clothing showing my new design;

FIG. 2 is a rear elevational view thereof;

FIG. 3 is a left side elevational view thereof;

FIG. 4 is a right side elevational view thereof;

FIG. 5 is a bottom plan view thereof; and,

FIG. 6 is a top plan view thereof.

The broken lines shown in FIGS. 5 and 6 represent the portions of the design which form no part of the claim.
